John M. Shaheen, New York, N. Y., assignor to Tele-Trip Policy Company, Inc., New York,
N. Y., a corporation of New York

Application February 18, 1950, Serial No. 8,003

Term of patent 14 years

(Cl. D52—3)

To all whom it may concern:

Be it known that I, John M. Shaheen, a citizen of the United States of America, residing at New York city, county of New York, State of New York, have invented a new, original, and ornamental Design for an Insurance Policy Vending Machine, of which the following is a specification, reference being had to the accompanying drawing, forming a part hereof.

In the drawing:

Figs. 1 and 2 are perspective views of an insurance policy vending machine, illustrating my new design.

Fig. 3 is a rear elevational view of the insurance policy vending machine shown in Figs. 1 and 2.

I claim:

The ornamental design for an insurance policy vending machine, substantially as shown.

JOHN M. SHAHEEN.
